PAPER FASTENER

John Clark Brown, Montclair, N. J., assignor to
Eastern Tool & Mfg. Co., Bloomfield, N. J., a
corporation of New Jersey

Application March 10, 1943, Serial No. 478,631

5 Claims. (Cl. 24—153)

This invention relates to an improved paper fastener for use in fastening loose sheets together, and particularly to a paper fastener structure suitable for construction from fiber material.

Paper fasteners ordinarily comprise a base member having paper-engaging prongs at its ends, and a compressor member having slots into which the prongs are inserted and then bent over parallel to the compressor, the base member cooperating with the compressor to hold loose sheets of paper together. Paper fasteners of this class have heretofore been constructed of metal, since it has been heretofore thought that only metal possessed the necessary strength and the necessary ability to retain its shape after bending which would give a paper fastener capable of holding papers firmly together.

It is an object of the present invention to provide a new paper fastener construction which may be made of a relatively stiff fiber material and which is so designed at the points of stress as to provide a fastener sufficiently strong to withstand the stresses to which it may be subjected without tearing of the fiber material and without slipping of the joint between the compressor and the tongues of the base member.

It is a further object to provide an improved compressor member constructed for improved locking engagement with a tongue of a base member of a paper fastener.

It is a further object to provide an improved form of base member having improved resistance to tearing.

Other objects will in part be described herein-after and in part shown in the accompanying drawing, in which:

Fig. 1 is a perspective view of an improved paper fastener involving the improvements of my invention.

Fig. 2 is a top plan view of a compressor member according to my invention.

Fig. 3 is a bottom plan view of a base member according to my invention.

Fig. 4 is a fractional enlarged sectional elevation taken on the line 4—4 of Fig. 1.

Fig. 5 is an enlarged sectional end elevation taken on the line 5—5 of Fig. 4.

Fig. 6 is a plan view showing a modified form of compressor according to my invention.

Fig. 7 is a fractional enlarged sectional elevation showing the cooperation of a base member and the compressor shown in Fig. 6.

Figs. 8 and 9 are plan views showing modified forms of compressors according to my invention.

In accordance with the present invention I

have provided a new paper fastener structure suitable for fabrication from fiber material and comprising a novel cooperating base member 10 and compressor member 12. The base member 10 has been designed with a new contour which eliminates rupture centers, so that it is of sufficient strength for use in cooperation with a compressor member to form a strong fastener device for securing papers together. The compressor member involves improved new structural features which cooperate with a base member and particularly with a fiber base member to lock the tongues 14 of the base firmly in the desired place, and to prevent slipping of the fiber tongues, notwithstanding the relative weakness of fiber material as contrasted with metal heretofore considered essential.

Referring to the drawing, Fig. 1 illustrates a paper fastener assembly comprising a base member 10 which may be of fibrous material, and a compressor member 12, which also may be of fibrous material, engaging the tongues 14 at the ends of the base member 10, and locking those tongues 14 firmly in place so that the base member 10 and compressor member 12 are firmly held in fixed spaced relation.

The compressor member 12 shown in Fig. 2 comprises stiff fiber material preferably formed with stiffening ridges 16 extending lengthwise along the edges thereof. Locking slots 18, preferably in a curved shape which may be substantially arcuate, are cut by a die without removal of material. The slots are disposed adjacent opposite ends of the compressor member for the reception of base member tongues 14. As shown in Fig. 4, the die cuts form lips 20 which may be bent out of the plane of the compressor 12 and which cooperate with the opposed edges 22 of the slots 18 as described below, to resist withdrawal of tongues which may be inserted through the slots. Pairs of opposed tongue-holding lips, 24 and 26 near one end of the compressor and 24' and 26' near the other end, are formed at the longitudinal sides of the compressor member 12; and the lips of each pair are spaced different distances from its respective nearest locking slot 18 of the compressor member 12.

A preferred form of the base member, shown in Fig. 3, comprises stiff fiber material having a relatively wide center portion 28 substantially corresponding in length to the distance between the locking slots 18 of the compressor member 12, and preferably having stiffening ribs 30 pressed in the fiber material extending lengthwise of the center portion 28 adjacent the edges. At both

ends of the wide center portion 28 are disposed relatively long narrow end portions or tongues 14 which engage paper sheets to be fastened, and hold them in place when the base member is assembled with the compressor. A stiffening rib 34 extends down the center of the base member from a position somewhat spaced from the end of one of the tongue portions 14 to a position somewhat spaced from the end of the other tongue portion 14. At the shoulders or junctures between the tongues 14 and the wide center portion 28 there are provided concave curved edges 32 of a conformation which has been found to distribute the stress which would normally be localized at these points, and to eliminate rupture points. As shown in Fig. 3, this curved contour preferably comprises a substantially arc-like portion tangent to the tongue and curving smoothly outward until it joins the edge of the wide center portion.

The assembly of the above described base member 10 and compressor member 12 and the locking action of the slots on the tongues 14 of the base member are shown in Fig. 4. This figure shows only the left-hand portion of the fastener assembly, since the compressor 12 is substantially the same at both ends. It will be understood that the tongues 14 and compressor 12 of the fastener are in the same relationship at the right end as at the left end. As shown in the drawing, the tongue portion 14 at the left end of the base member 10 is bent up at right angles as it would be for the reception of a pile of papers which would be inserted over the tongues. The tongue 14 extends upwardly through the locking slot 18, and is bent over around the lip member 20 to a position parallel and in juxtaposition to the upper face of the compressor member. A portion 36 of the tongue 14 is displaced out of alignment with the slot 18 by the end of the locking lip 20, so that downward withdrawal movement of the tongue is resisted by the displaced portion 36 of the tongue 14. The lip member 20 is flexible so that any withdrawal movement of the tongue 14 from the slot 18 moves the lip 20 downwardly and exerts a squeezing, braking action between the end of the lip member 20 and the opposite edge 22 of the slot 18, which effectively prevents further withdrawal of the tongue from the slot. Also, the tongue is bent sharply around the end of the lip member so that the stiffness of the tongue aids and strengthens the joint.

To hold the tongue 14 firmly in place flat against the compressor 12, the tongue-holding lip members 24 and 26 are positioned and spaced different distances from the slot 18. The space between the slot 18 and the closest tongue-holding lip member 24 is such that the edge of the tongue 14 can be introduced beneath the lip member 24 by twisting the tongue angularly counterclockwise about the slot, depressing it, and slipping it underneath the lip member 24; and the space between the lip member 26 and the lip member 24 and slit 26 is sufficient that the tongue 14 can be inserted beneath the second tongue-holding lip member 26 by twisting the tongue 14 angularly clockwise about the slot and then slipping the edge of the tongue under the edge of the second lip member. As best shown in Fig. 5, the ends of the lip members 24 and 26 are spaced from the lateral center of the compressor a distance substantially corresponding to half the width of the rib 34 on the tongues 14 and cooperate to hold the tongue 14 firmly in place. It is also noted that the lateral strengthening ribs 16 at the sides of the compressor 12 engage

the edges of the tongue 14 and also resist lateral displacement of the tongue 14.

It is to be understood that it is not necessary that the locking engagement between the tongue and compressor be the same at both ends, but that one form of locking engagement, e. g., similar to that above described, may be provided at one end of the compressor, and another form at the other. A compressor 40 giving this locking action is shown in Fig. 6, and the modified locking action is shown in detail in Fig. 7. As shown in Fig. 6, the left-hand end of the compressor 40 is identical with that of the compressor 12 shown in Fig. 2, and functions in exactly the same way.

The right hand of the compressor 40 involves an arcuate slot 42 similar to the slot previously described, but differing from that slot in that the lip 44 formed by the cut is bent downwardly from the plane of the compressor. In the assembly of a base member 10 with this compressor (see Fig. 7), the tongue member 14 is bent over around the outside of the end 41 of the compressor 40 and projects downwardly through the locking slot 42 in the compressor, and then extends inwardly and in parallel juxtaposition to the inner face of the compressor member 40. This connection is formed by holding the compressor member 40 upside down with the end 41, which will ultimately be the left-hand side, at the right, and inserting the right-hand tongue 14 of the base member 10 through the locking slot 42 and bringing the end 41 of the compressor member down into contact with a pile of papers to be fastened by the paper fastener. The compressor 40 is then swung around the end 41 which will eventually be the right-hand end of the compressor, bending the tongue member 14 to the conformation above described and locking the tongue 14 and compressor 40 firmly together. As shown in the drawing the arcuate locking slot 42 forms a locking tongue member 44 which is depressed below the plane of the compressor, and which presses the tongue 14 of the base member inserted through the slot so that portions 46 of it extend out of alignment with the slot and serve to resist withdrawal of the tongue from the slot. Also, because of the flexibility of the lip member 44 any withdrawal movement of the tongue member 14 bends the lip member back towards a position in alignment with the compressor, and exerts a sharp squeezing braking action between the end of the lip member 44 and the opposite edge of the slot which effectively prevents withdrawal of the tongue from the slot.

It is particularly to be noted that in the joint formed at the right-hand of the compressor member as above described, the tongue is bent sharply around the edge of the locking slot 42, and also bent sharply (almost 180°) around the locking tip 44 to provide an exceptionally satisfactory locking engagement.

According to another embodiment of my invention (see Fig. 8), the compressor may have a locking slot 50 comprising a simple straight line cut 52 having cross cuts 54 at the ends thereof to form a rectangular tongue 56 of which the free end is bent out of the plane of the compressor. This compressor will be used in substantially the same way as the preferred form, i. e., a tongue 14 of a fastener base 10 will extend upwardly through the locking slot 50 and will be bent over around the tongue 56 to a position parallel to and in juxtaposition to the upper face of the compressor member. A portion of the tongue 14 will be displaced out of alignment with the

slot 50 by the end of the locking tongue 56, so that downward movement of the tongue 14 is resisted by the displaced portion. Also, the tongue 56 is flexible so that any withdrawal movement of the tongue 14 from the slot 50 moves the tongue 56 downwardly and exerts a squeezing, braking action between the end of the tongue member 56 and the opposite edge of the slot 50, which effectively prevents further withdrawal of the tongue from the slot.

In the construction shown in Fig. 8, additional slots 57 are spaced inwardly from the locking slots 50 to receive the ends of the tongues 14 of the fastener base which will be inserted therethrough in a downward direction and will be held thereby parallel and in juxtaposition to the compressor.

When subjected to stress, both the compressor having arcuate locking slots and the compressor having a square cut locking tongue will resist withdrawal of the tongue up to the point where the lip 22 of the arcuate locking slot or the tongue 56 of square cut locking slot is pulled back through the opening and bent below the plane of the compressor. It is found in practice that with the square die-cut the tongue 56 acts like a hinge and pulls through the locking slot at much lower stresses than does the lip 20 of the arcuate locking slot. This is apparently due to two mechanical advantages present in the arcuate locking slot. In the first place, it will be apparent that the longer the lip or tongue, the more stock there is to be compressed or bent by stress, and the weaker the locking action. In the arcuate cut the length of the lip as measured from the line connecting its bases, i.e., the ends of the locking slot, progressively decreases towards the sides of the locking lip 20 so that the tongue is strongest and exerts its most effective locking action at the sides, whereas in a square cut locking slot the length of the tongue at the square shoulders is the same as at the center of the tongue, so that there is not obtained the increased strength of locking action. In the second place, in the arcuate locking slot every portion of the edge of the locking lip 20 is supported at both sides against bending, whereas in the square cut locking slot the sides of the square shoulders of the tongue 56 are unsupported.

The above advanced explanations of the very much greater locking strength of the arcuate locking slot over the square cut locked slot are merely advanced as theories and probably explanatory of the improved action of the arcuate slot. Applicant does not wish, however, to be bound by these theories, since the actual fact is that the arcuate locking slot does give a stronger joint (up to 50% stronger) no matter what the true explanation may be.

However, while the square cut locking slot is not as efficient or satisfactory as the arcuate slot, it possesses sufficient strength for some uses and applicant does not wish to be understood as excluding this construction from the scope of those of the claims appended hereunto which are not limited to the arcuate slot.

In the embodiments above described, the compressor has been described as having the free end of the locking lip or tongue member bent from the plane of the compressor. It is not, however, necessary that the lip or tongue be bent in the manufacturing operation, and only a simple cut may be formed in the compressor. Where the locking tongue or lip is not bent during manufacture, it may be lifted upwardly, for example,

by a slight finger operation, to permit entry of the tongue 14 of the base member.

These locking slots are preferably formed by simple die cuts without removal of any material along the line of cut, since it is found that with the ordinary fiber a better locking action between the end of the lip member and the opposite edge of the slot is obtained thereby. However, it may be found with other materials, or to suit manufacturing convenience, that it is desirable to remove some amount of material in making the locking slot, and it is to be understood that such construction is considered within the scope of the present invention, provided that the space between the opposite edge of the slot and the end of the lip member is such as to secure locking action such as above described.

Other forms of tongue-holding lips may be employed. As shown in Fig. 9, these may comprise lip members 60 extending from the side of the compressor 62 and spaced from the ends of the compressor, under which lip members 60, tongues 14 of a base member 10 may be inserted to hold the tongues 14 in place. These tongue-holding members 60 hold the tongues resiliently in depressed position so that the edges of the tongues 14 abut the strengthening ridges 64 at the sides of the compressor to assist in holding the tongues in place. It has been found highly desirable that both of the tongue-holding lips 60 be disposed on the same side of the compressor as shown in Fig. 9, and that when such a compressor is assembled with a base member, that the compressor be positioned with the tongue-holding lips 60 projecting away from the main body of the papers enclosed in the paper fastener. By this arrangement, applicant has found that stress on the paper fasteners tends to move the tongues 14 into closer engagement with the tongue-holding lips 60, whereas arrangement of the tongue-holding lips 60 on opposite sides of the compressor or arrangement of the compressor member with the lip-holding members extending down towards the body of the paper will result in displacement of the tongue 14 from under the tongue-holding lips 60 when the paper fastener is subjected to stress.

From the above description, it is apparent that the applicant has provided a new type of paper fastener suitable for construction of fiber, having improved tongue-locking and tongue-holding devices, while involving very simple construction and a minimum of separate parts. Actual tests of the fiber fastener in comparison with other types of other fiber paper fasteners have demonstrated conclusively that the present paper fastener possesses an exceptionally high paper-holding ability. In a standard test for strength of the paper fasteners, a sheaf of 8 1/2 x 11 papers are bound together by means of a paper fastener.

The free ends of the sheets of paper are perforated and a cord passed through half of the sheets and secured to a support, and a second cord is passed through the remaining sheets and connected to a weight, so that the sheaf of papers is spread open similar to the opening of a book, to exert rupturing stress on the paper fastener. With previous fiber fasteners, a weight of three to four pounds will usually cause a slippage of from 1/8 to 1/4 inch, and in most fiber fasteners under weight of about 8 pounds the tongues will pull entirely away from the compressor, letting the two sections of the paper fall apart. With the new fiber fastener involving the combination of the compressor with the new locking slots and the improved base, there is no slippage, or prac-

tically no slippage, even at weights up to 18 pounds. It is pointed out that the base member capable of standing high stresses departs from the customary diagonally extending shoulder between the tongues and wide center portion of the base member, and uses a concave curve tangent to the tongue which prevents rupture. This is contrary to accepted practice which has heretofore regarded it as important to provide a definite shoulder to prevent displacement of bound papers onto the base, but it has been found that because of the type of bend formed in fiber material, the improved edge contour at this point satisfactorily avoids this difficulty.

Numerous modifications may be made in the structure shown in the attached drawing and described hereinabove. For example, the base might be made in two or more sections, e. g., with the tongue portions separate from the wider portion of the base. It is to be understood that the present invention is not to be restricted to the specific embodiments shown, but is intended to cover all structures which as a matter of language may be held to fall within the claims appended hereto.

The term "fiber" as used in the specification and claims is intended to include not only the material technically known as "fiber," but also similar relatively stiff strong material, preferably of fibrous nature.

I claim:

1. A paper fastener constructed of fiber material comprising a base member and a compressor member cooperating therewith, said base member having a wide center portion and long narrow end portions forming paper-engaging tongues, a raised rib extending lengthwise of the tongues, and smoothly curved edges tangent to the tongues joining the center portion and the tongues of said base, and said compressor member being formed to provide an arcuate slot adjacent each end in which are disposed the tongues of the base member, an edge of each slot providing a lip of which the free end engages the tongue disposed in the slot and cooperates with the opposed edge of the slot to resist withdrawal movement of the tongue, the compressor member also comprising at each end pairs of lip members extending over the compressor from opposite lengthwise sides thereof, each of said pairs of lip members being constructed and arranged to engage the tongue inserted through the slot nearest it, which tongue is bent to a position parallel to the compressor, and to hold the tongue beneath it to prevent accidental displacement of the tongue, the lips of each of said pairs of lips being spaced from their respective nearest slots lengthwise of the compressor at different distances, whereby the spaces between said slots and the closest lips and between the closest lips and second lips are sufficient for insertion of the tongue under the successive lips by angular movement of the tongue.

2. A paper fastener constructed of fiber material comprising a base member and a compressor member cooperating therewith, said base member having a wide center portion and long narrow end portions forming paper-engaging tongues, a raised rib extending lengthwise of the tongues, and smoothly curved edges tangent to the tongues joining the center portion and the tongues of said base, and said compressor member being formed to provide an arcuate slot ad-

jacent each end, in which are disposed the tongues of the base member, an edge of the slot at one end being formed to provide a lip of which the free end engages the tongue disposed in the slot and cooperates with the opposed edge of the slot to resist withdrawal movement of the tongue, the compressor member also comprising lip members extending over the compressor from opposite lengthwise sides thereof, said lip members being constructed and arranged to engage said tongue, which tongue is bent to a position parallel to the compressor, and to hold the tongue beneath them to prevent accidental displacement of the tongue, said lips being spaced from the slot lengthwise of the compressor at different distances whereby the spaces between said slot and the closest lip and between the closest lip and the second lip are sufficient for insertion of the tongue under the successive lips by angular movements of the tongue, an edge of the slot in the compressor member adjacent the other end being formed to provide a lip of which the free end is adapted to engage a tongue inserted through the slot and to cooperate with the opposite edge of the slot to resist upward movement of the tongue, the second tongue of said base extending around the end of the compressor and downwardly through the slot in locking engagement with the lip and the edge of the slot opposite the lip, and then extending parallel and in juxtaposition with the inner face of the compressor.

3. A paper fastener comprising a base member and a compressor member cooperating therewith, said base member having a wide center portion and long narrow end portions forming paper-engaging tongues, and said compressor being formed to provide an arcuate slot adjacent one end for the passage of a tongue of the base member, an edge of said slot being formed to provide a lip of which the free end is adapted to engage a tongue inserted through the slot and to cooperate with the opposed edge of the slot to resist upward movement of the tongue, said base and compressor being assembled with a tongue of said base extending around the end of the compressor and downwardly through the slot in locking engagement with the lip and the edge of the slot opposite the lip, and then extending inwardly parallel and in juxtaposition to the inner face of the compressor.

4. A paper fastener compressor member arcuately cut to form a slot adjacent each end of the compressor, an edge of the slots at each end providing resilient lips of which the free end of the lip at one end is bent upwardly and the free end of the lip at the other end is bent downwardly from the plane of said compressor, the width of said slots being such that said lips frictionally engage tongues inserted through said slots and cooperate with the opposed edges of the slots to resist withdrawal movement of the tongues.

5. A paper fastener compressor member arcuately cut to form a slot adjacent each end of the compressor, an edge of the slots at each end providing resilient lips of which the free ends are bent upwardly, the width of said slots being such that said lips frictionally engage tongues inserted through said slots and cooperate with the opposed edges of the slots to resist withdrawal movement of the tongues.

JOHN CLARK BROWN.
